[57] ABSTRACT

A pencil sharpener is described including a fastening-pin assembly comprising a bore-defining fastening pin, having a pencil-sharpening blade therein. The fastening pin's bore is funnel shaped for receiving pencil points to be sharpened. In one embodiment the fastening-pin assembly comprises a tubularly shaped rivet with a pencil sharpening blade assembly mounted therein. The rivet pencil sharpener is described in combination with a folding ruler wherein several rivet assemblies are located at pivotal joints of the folding ruler. When the folding ruler is folded so as to line up the pivotal joints, the rivet assemblies cooperate to form a pencil sharpener. The rivet pencil sharpener is also described in combination with a tape ruler wherein it is mounted at the axis about which a roll of tape rotates. In another embodiment, the fastening pin assembly comprises a tubularly shaped bolt, having a pencil sharpening blade mounted therein and being fastened to objects with a nut.

PENCIL SHARPENING DEVICE

BACKGROUND OF THE INVENTION

This invention relates generally to the pencil sharpener art and more particularly to pencil sharpeners which are combined with other objects such as rulers and various other tools.

Workmen, such as carpenters, use pencils from time to time along with many other tools. When such pencils must be sharpened it is often inconvenient for the workmen to seek pencil sharpeners or penknives.

A prior art method for making pencil sharpeners conveniently accessible to workmen, is to combine a portable pencil sharpener with a tool. For example, U.S. Pat. No. 503,794 to Holben, and U. S. Pat. No. 822,553 to Reizenstein describe portable type pencil sharpeners combined with rulers. One difficulty with many such prior art pencil sharpeners is that the shapes of their outer housings are not particularly suited for easy attachment to other tools. It is therefore an object of this invention to provide a pencil sharpener having an outer housing which is particularly shaped for easy attachment to other tools.

Also, a disadvantage of some prior art pencil sharpener combination devices is that their shapes and sizes are inconveniently large. For example, in the device described in the Holben patent a ruler block must be relatively thick to accommodate a pencil-sharpener cavity, and in the device described in the Reizenstein patent a conical pencil sharpener is attached on the outside surface of a ruler's handle. Especially in the case of Reizenstein, the pencil sharpener protrudes from the tool and thereby detracts, to some degree, from its overall usefulness. It is therefore another object of this invention to provide a pencil sharpener which is mountable on many tools, particularly measuring tools, and which, when so mounted, does not significantly increase the size, or detract from the usefulness, of such tools.

Many popular tools comprise sections which rotate about axes, such as folding rulers or tape rulers. Although such tools are often used by handymen and carpenters, pencil sharpeners are seldom combined with them; most likely because it is difficult to mount pencil sharpeners on them without interfering with their moving sections. It is therefore yet another object of this invention to provide a practical combined tool which comprises a pencil sharpener mounted on a tool having rotatable sections.

SUMMARY OF THE INVENTION

According to the principles of this invention a pencil sharpener includes a tubularly shaped fastening pin having a pencil sharpening blade mounted therein.

Such fastening-pin pencil sharpeners when in the form of rivets, are particularly suited to be mounted at the axes areas of tools having rotating sections. For example, pencil sharpening rivet assemblies can be combined with folding rulers by respectively locating several rivet assemblies at pivotal joints of the folding rulers. When the folding rulers are folded such that the pivotal joints are lined up adjacent one another the rivet assemblies cooperate to form rivet pencil sharpeners. The rivet pencil sharpeners can also be combined with tape rulers by mounting them at the axes areas of such tape rulers.

Further, such fastening-pin pencil sharpeners, when in the form of bolts, are particularly suited to be mounted by users thereof on any structural objects having holes therein. For example, carpenters can bore holes in ladders' sidepieces and mount pencil sharpening bolts therein.

BRIEF DESCRIPTION OF THE DRAWINGS

The foregoing and other objects, features and advantages of the invention will be apparent from the following particular description of preferred embodiments of the invention, as illustrated in the accompanying drawings in which reference characters refer to the same parts throughout the different views. The drawings are not necessarily to scale, emphasis instead is placed on illustrating the principles of the invention in a clear manner.

FIG. 1 is an isometric view of two sections of a standard folding ruler having a rivet assembly, employing principles of this invention, mounted therein.

FIG. 2 is an exploded view of the rivet assembly and two folding ruler joint members shown in FIG. 1.

FIG. 2A is a sectional view of the rivet assembly taken on line 2A—2A in FIG. 2;

FIG. 3 is a sectional view taken on Line 3—3 in FIG. 1;

FIG. 4 is a sectional view of a folded, folding ruler having rivet assemblies employing principles of this invention mounted therein, while used to sharpen a pencil the section being taken from a direction as indicated by line 4,5 — 4,5 in FIG. 3 relative to element 11c;

FIG. 5 is a sectional view of a folded, folding ruler having rivet assemblies employing principles of this invention mounted therein, similar to FIG. 4, but while in a "protected" configuration;

FIG. 6 is an isometric view of a tape ruler assembly having a rivet pencil sharpener mounted therein;

FIG. 7 is an exploded sectional view of a bolt assembly employing principles of this invention; and

FIG. 8 is an exploded isometric view of the bolt assembly of FIG. 7 mounted on a ladder.

DESCRIPTION OF THE PREFERRED EMBODIMENTS

Referring to FIGS. 1-5, there is shown a pencil sharpener fastening pin assembly in the form of rivet assemblies 11a, b and c mounted at the pivot joint of a standard folding ruler 13.

Referring first to FIGS. 1-3, the pencil sharpener rivet assembly 11c comprises a cylindrically shaped outer housing 15, a blade member 17, a guide member 19 and first and second flanges 21 and 23. In the preferred embodiment the rivet assembly, including the blade member 17 and the guide member 19, is an integrated structural member. The blade member 17, the guide member 19 and walls of the outer housing 15 define a funnel shaped bore 25. The blade member 17 and guide member 19 are positioned relative to one another such that if an elongated instrument, such as a pencil, is inserted into the funnel shaped bore 25 and rotated in a counterclockwise direction, as seen in FIG. 4, a cutting edge 27 of the blade member 17 (shown in FIGS. 1-3, but not in FIG. 4) sharpens the instrument.

The standard folding ruler 13 comprises many sections with adjacent sections being pivotally joined together by rivets. The folding ruler sections are desig-

nated by numerals 29-47 in FIG. 5. Two of the ruler sections 41 and 43, are shown in more detail in FIG. 1 in the "unfolded" configuration.

As can be seen in FIGS. 1 and 2, two joint members 49 and 51 are respectively mounted on the ruler sections 41 and 43 by prongs 53 and beveled sides 54. The ruler sections 41 and 43, along with joint members 49 and 51, are pivotally joined by the pencil-sharpener rivet assembly 11c which is inserted through joint-member bores 55 and bores in the ruler sections (as shown in FIG. 3). The first and second rivet flanges 21 and 23 are flattened as shown in FIG. 3 to hold the ruler sections 41 and 43 together. Bosses 57 in the second joint member 51 cooperate with cavities (not shown) in the first joint member 49 to retain the ruler sections 41 and 43 in an "unfolded" position as shown in FIG. 1 or in a "folded" position as shown in FIGS. 4 and 5.

With regard to the overall combination folding ruler/rivet pencil sharpener, rivet assemblies 11a, b, and c are mounted at every other pivot joint of the folding ruler 13, with respective blades (not shown in FIGS. 4 and 5), guides 19 and h housing walls of each sequential rivet assembly defining a funnel shaped bore 25 which is progressively smaller, or larger, than the preceding rivet assembly bore. In this manner, when the folding ruler is folded, as shown in FIG. 4, the pencil sharpener rivets are lined up and can be used to sharpen a pencil 59.

In FIG. 5 there is shown the same folded, folding ruler seen in FIG. 4 but with additional end sections 29, 31, 45 and 47 joined by prior art rivets 61. It should be noted that these rivets do not extend through the ruler sections 29, 31 and 45, 47 as do the pencil sharpening rivets 11. When the folding ruler is folded, as shown in FIG. 5, these sections close over the ends of the end pencil sharpener rivets 11a and 11c and thereby help to protect the rivet assemblies 11a-c.

Shown in FIG. 6 is a pencil sharpener rivet assembly 67 mounted in a tape ruler assembly 69. The rivet pencil sharpener shown in FIG. 6 has a single cutting edge 71 (as opposed to the segmented cutting edges of the rivet pencil sharpener shown in FIGS. 4 and 5) and a single guide member 73. That is, the rivet assembly 67 forms a complete pencil sharpener which does not cooperate with other rivet assemblies.

Referring now to FIGS. 7 and 8, there is shown a pencil-sharpener fastening pin assembly in the form of a bolt assembly 75. The bolt assembly 75 comprises a tubularly shaped bolt 76 having a pencil sharpening blade 77 and a guide member 79 mounted therein. In this regard, it should be noted that FIG. 7 is a sectional view similar to the sectional views of FIGS. 4 and 5. That is, it is taken looking away from a blade which cannot be seen in this drawing, toward a guide member 79. The bolt assembly 76 is externally threaded and has a bolt head 81 with lock teeth 83 protruding therefrom. A nut 85, for mating with the bolt 76, has a nut head 87 and an internally threaded nut body 89.

The manner of installing the pencil-sharpening bolt assembly 75 is shown in FIG. 8. After an appropriately sized hole 91 is bored in a structural member, such as a ladder's sidepiece 93, the nut body 89 is inserted into one end of the hole and the bolt 76 is screwed tightly into the nut from the other end of the hole. Thus, the bolt and nut heads 81 and 87 are tightened on the sides of the ladder's sidepiece 93 and hold the bolt assembly

75 firmly in place. A lock washer 95, mounted on the nut body 87, and the lock teeth 83, prevent the bolt assembly 75 from coming unscrewed during use.

In operation, a pencil tip is inserted into a pencil receiving cavity 97 and is rotated so that the blade 77, positioned opposite the guide member 79, slices shavings from the pencil tip. The shavings are exhausted via a shavings cavity 99. It will be appreciated by both handymen and professional workmen that the fastening-pin pencil sharpeners described herein are unusually useful and convenient. For example, some such pencil sharpeners can be easily self mounted by workmen on various tools. Further, by mounting fastening-pin pencil sharpeners at the pivotal areas of tools having pivot joints, useful and convenient tools are created.

While the invention has been particularly shown and described with reference to preferred embodiments, it will be understood by those skilled in the art that various changes in form and detail may be made therein without departing from the spirit and scope of the invention. For example, pencil sharpener rivet assemblies can be easily mounted on numerous tools not mentioned above. Further, a fastening-pin pencil sharpener can comprise various combinations of fastening pins and blades interconnected in various manners.

The embodiments of the invention in which an exclusive property or privilege are claimed are defined as follows:

1. A pencil sharpener of the type which is adapted to be mounted inside a smooth bore in a structural member, said pencil sharpener comprising:

a first tubularly-shaped member having an outwardly extending flange or head at a first end thereof, said first tubularly shaped member having external threads formed on the outer surface thereof, and having, on the inside thereof, a guide member and a pencil sharpening blade, said guide member and said pencil sharpening blade cooperating to form a cone-shaped pencil-receiving cavity on a first side thereof and a shavings cavity inside said first tubularly shaped member on a second side thereof, said pencil-receiving cavity having an enlarged portion opening toward said first end of said first tubularly shaped member and said shavings cavity having an enlarged portion opening toward a second end of said first tubularly shaped member, whereby a pencil can be inserted into said pencil-receiving cavity and rotated to sharpen said pencil;

a second tubularly-shaped member having an outwardly extending flange or head at a first end thereof, said second tubularly-shaped member being hollow and having internal threads formed on an inner surface thereof, said second tubularly shaped member having a relatively smooth outer surface and being adapted to fit into said smooth bore; whereby

said second-tubularly shaped member can be inserted into said smooth bore from a first end of said bore until said second-tubularly shaped-member flange or head contacts said structural member, and said first tubularly shaped member can be screwed into said second tubularly shaped member from a second side of said bore until said first tubularly shaped member head contacts an opposite side of said structural member to thereby retain said pencil sharpener in said smooth bore.

2. A pencil sharpener as claimed in claim 1 wherein lock teeth protrude from the inside surface of at least one of said first tubularly shaped-member head and said second tubularly shaped-member head.
